CLAIM

The ornamental design for a cake gift box, as shown and described.

DESCRIPTION

FIG. 1 is a perspective view of a cake gift box showing my new design;

FIG. 2 is a top plan view thereof;

FIG. 3 is a front elevational view thereof, the rear elevational view being a mirror image;

FIG. 4 is a right side elevational view thereof, the left side being a mirror image; and,

FIG. 5 is an exploded, perspective view thereof showing the interior of the gift box.

The bottom plan view is plain and unornamented.
